UNITED STATES PATENT OFFICE.

EDWARD P. BAIRD, OF EVANSTON, ILLINOIS, ASSIGNOR, BY MESNE ASSIGNMENTS, TO THE KING LOCK COMPANY, OF CHICAGO, ILLINOIS, A CORPORATION OF ILLINOIS.

KEY-CONTROLLED LOCK.

1,280,633.

Specification of Letters Patent.

Patented Oct. 8, 1918.

Application filed January 28, 1914. Serial No. 814,334.

To all whom it may concern:

Be it known that I, EDWARD P. BAIRD, a resident of Evanston, in the county of Cook and State of Illinois, have invented certain new and useful Improvements in Key-Controlled Locks, of which the following is a full, clear, and exact description.

The invention relates to key-controlled locks.

10 The invention designs to provide a lock which is simple in construction and which cannot be operated except by a properly formed key.

15 A further object of the invention is to provide a lock which is operated by a spiral key.

20 A further object of the invention is to provide a lock, which contrary to usual practice, is made by constructing the lock to fit a previously made key.

The invention consists in the several novel features hereinafter set forth and more particularly defined by claims at the conclusion hereof.

25 In the drawings: Figure 1 is a front view of a lock embodying the invention. Fig. 2 is a rear elevation thereof. Fig. 3 is a section taken on line 3—3 of Fig. 2, the key being shown in position to release the tumblers. Fig. 4 is an end elevation of the key. Fig. 5 is a section taken on the line 5—5 of Fig. 3. Fig. 6 is a section taken on the line 6—6 of Fig. 8. Fig. 7 is a plan view of the spindle inserted in the cylinder which is shown in section. Fig. 8 is a section taken on the line 3—3 of Fig. 2, the key being withdrawn. Fig. 9 is a perspective view of the spindle key. Fig. 10 is a side view of the spiral key.

30 The lock is shown as secured to a plate 10 and comprises a barrel 11 which is secured to said plate by screws 12. The barrel comprises a hollow cylindrical member having oppositely disposed covered slots or ways 13 and 13' and a shoulder 14 in one of its ends.

A key spindle 15 is adapted to fit snugly within said barrel and to engage the shoulder 14. This spindle 15 is provided with a slot 16 extending transversely therethrough.

35 At one end, the spindle has a slot or guide 18 adapted to receive the end of the key 18a. The other end of the spindle is recessed as at 19 and a key-guide 20 is placed in this end. The key being spiral, it is necessary that this

guide 20 be first fitted to the key before inserting and securing it to the key-spindle. When in position, it serves as a guide for the key causing it to execute a rotary motion when the key is being inserted in the key-spindle. A spiral key adapted for this lock 55 is more particularly described in my Patent No. 1,161,760, dated November 23, 1915. The guide 18 is also formed in the spindle so that after the key has been inserted therein the end which has been rotated by its insertion in and by guide 20, now passes through guide 18. The position of these guides in the spindle makes it impossible to operate the lock by any other key than the one having the same twist as that by means of which the 60 guides were formed.

A series of tumbler-plates 22 are placed in slot 16 of spindle 15. Each tumbler is formed out of a thin strip or sheet of metal and comprises a flat plate having a longitudinal slot 23 therein and which is adapted to move transversely within and through the slot 16. These tumblers are adapted to pass into the covered slots 13 and 13' in the barrel to lock the spindle and the tumblers against 75 rotation. A number of the foremost tumblers are provided with extensions 24 which fit into a recess 25 in a slidable locking-bolt 26, the operation of which is controlled by the lock. These extensions serve to shift the 80 bolt when the spindle and tumblers are rotated. A ring 30 abuts against the end of barrel 11 and the shoulder 31 of the spindle and is secured to the spindle 20 by upsetting the edge of the spindle, as at 32. The ring 90 30 cooperates with the shoulder 14 to hold the spindle in the barrel 11 and covers the slots 13 and 13'.

The key 18a, which is adapted to be inserted into a narrow slot 28 in the guide 20 in the spindle 15, has its opposite edges formed of irregular but corresponding outline, so that its width at all points will correspond to the length of the slot 23 in each tumbler. Key 18a has a groove 29 therein, and the slots 28 and 18 in the spindle are correspondingly formed to guide the key in the spindle. The key is twisted along its length, so that when inserted in the lock, it will have a spiral movement and so that, should anyone wish to 100 duplicate the key, though they might make a key having a groove therein and its opposite edges formed of corresponding irregular

outline, still if they did not twist it the same as the original, it would not fit the slots 28 in the guide 20 and the slot 18 and therefore could not operate the lock. The slot 18 and 5 the guide-slot 28 serve to hold the key securely in place and to center it on the spindle when it is inserted therein so that it will have a positive action upon the spindle and the tumbler plates 22 when it is rotated to shift 10 the locking bolt 26. When the projecting edge-portion of the key moves one end of the said tumblers outwardly, the opposite end of the same tumbler will be free to move inwardly a corresponding extent by reason of 15 the parallel edged key.

In this manner, the tumblers are positively shifted and controlled by the key without the use of springs. The tumblers are confined against axial movement between 20 the ends of the slot 16 in the barrel 11 by one another.

In making the lock, the tumblers are all stamped of the same shape with slots 23. The spiral key will then be made with 25 parallel edges, but of any desired contour and twist. The spiral key, or a form like the key, is then inserted into the desired number of assembled tumblers and with the entire series of tumblers for the lock adjusted 30 to the key, the projecting portions of the tumblers will be cut off on a straight line, so that when the key has been inserted in the slot 28 and 18 of the specially constructed guides and is in the spindle, all the 35 tumblers will clear the slots 13 and 13' in the barrel and be free to rotate in the barrel and operate the locking-bolt 26. By such a method of construction, the release of the lock by a key of any form to which the 40 tumblers and guides are fitted is insured and this saves any fitting of the key to the lock.

The invention is not to be restricted to the details set forth, since these may be modified within the scope of the appended claims without departing from the spirit and scope of the invention.

Having thus described the invention, what I claim as new and desire to secure 50 by Letters Patent, is:

1. In a lock of the kind described and in combination, a fixed barrel, a locking bolt, a spindle having a key guide therein, a series of tumbler plates within said spindle 55 provided with slots arranged at the ends to be engaged by the key for controlling the tumblers, said slots of a size to permit a partial rotation of the key relative to the tumblers, said tumbler plates movable in directions to engage the fixed barrel and retain the spindle against rotation when the plates are shifted by said key, and means for operatively connecting the spindle and locking bolt.

2. In a lock of the kind described and in combination, a fixed barrel, a spindle in the barrel having a key guide therein, a series of key controlled tumbler plates within said spindle provided with slots and arranged to be engaged thereat by the key for controlling the tumblers in opposite directions, said slots being of greater width than the thickness of the key whereby the key may have a turning movement therein, said spindle having a longitudinal slot in which 75 said tumblers reciprocate, said barrel having means for receiving the tumbler plates when they are shifted by said key, a locking bolt, and means for transmitting movement of said spindle to said locking bolt. 80

3. In a lock of the kind described, the combination of a series of perforated tumbler plates having surfaces intermediate the ends thereof arranged to be engaged by a key to operate said tumblers, said perforations in said plates being of a size to permit a turning of the key relative the plates, and means at one side of said plates for guiding the key whereby the key is caused to turn relatively to the tumblers upon insertion of the key in said guide and lengthwise movement of the same through said perforations. 85

4. A lock comprising a rotatable spindle, a fixed barrel for containing said spindle, and a series of tumbler plates mounted in said spindle and movable to engage said barrel, said spindle having a key guide at one end and a centering plate at the other, and said tumbler plates provided with suitable key-ways therethrough adapted to be engaged by a spiral key upon insertion of the key therethrough, said key-ways of greater width than the thickness of the key whereby a partial rotation of the key 105 when in said key-ways is permitted, a locking bolt, and means for transmitting movement from said spindle to said bolt.

5. In a lock, a spindle having a key guide at one end thereof, a series of tumbler plates mounted on said spindle, a key for shifting said tumblers in opposite directions, said tumbler plates provided with slots therein which are of greater width than the thickness of the key whereby the key may be inserted through the slots to shift the tumblers, and the key will be free to partially turn in said slots. 110

6. A lock comprising a fixed barrel, a spindle having a key guide at one end thereof, a series of tumbler plates provided with slots having surfaces adapted to be engaged by a key whereby the tumblers are shifted upon insertion of the key, said spindle having a longitudinal slot therein in which 120 said tumblers reciprocate, said barrel arranged for receiving the ends of said tumbler plates when they are shifted in oppo- 125

site directions by said key, said spindle having a key guide at its inner end conforming to the contour of the inner end of the key and disposed to receive a particular key 5 suitable for operatively shifting the tumblers, and means mounted on the inner end of said spindle and engaging the inner end

of the fixed barrel for preventing transverse movement of the inner barrel.
